US00D886683S

(12) **United States Design Patent** (10) **Patent No.:** **US D886,683 S**
(45) **Date of Patent:** **** Jun. 9, 2020**

(54) **BABY TRAILER CONNECTOR**

(71) Applicant: **Shenzhen Heibaihong Electronic Commerce Co., Ltd.**, Shenzhen (CN)

(72) Inventor: **Teng-Hui Hong**, Shenzhen (CN)

(73) Assignee: **Shenzhen Heibaihong Electronic Commerce Co., Ltd.**, Shenzhen (CN)

(**) Term: **15 Years**

(21) Appl. No.: **29/650,787**

(22) Filed: **Jun. 8, 2018**

(51) LOC (12) Cl. **12-10**

(52) U.S. Cl.

USPC **D12/106**; D12/223; D12/114

(58) **Field of Classification Search**

USPC D8/349, 354, 382, 396; D12/106, 114, D12/115, 117, 113, 223, 129, 133

CPC B62K 27/10; B62K 27/12; B62K 27/14; B62K 27/003; B62B 7/126; B62B 7/142

(57) **CLAIM**

The ornamental design for a baby trailer connector, as shown and described.

DESCRIPTION

FIG. 1 is a front perspective view of a baby trailer connector showing the claimed new design;

FIG. 2 is a rear perspective view of the baby trailer connector of FIG. 1;

FIG. 3 is a front elevation view of the baby trailer connector of FIG. 1;

FIG. 4 is a rear elevation view of the baby trailer connector of FIG. 1;

FIG. 5 is a left side elevation view of the baby trailer connector of FIG. 1;

FIG. 6 is a right side elevation view of the baby trailer connector of FIG. 1;

FIG. 7 is a top plan view of the baby trailer connector of FIG. 1; and,

FIG. 8 is a bottom plan view of the baby trailer connector of FIG. 1.

1 Claim, 8 Drawing Sheets
